DESIGN FOR AN INSTRUMENT CASE OR SIMILAR ARTICLE

William A. Baum, Forest Hills, N. Y.

Application November 6, 1936, Serial No. 65,722

Term of patent 7 years

To all whom it may concern:

Be it known that I, William A. Baum, a citizen of the United States, residing at Forest Hills, in the county of Queens and State of New York, have invented a new, original, and ornamental Design for Instrument Case or Similar Article, of which the following is a specification, reference being had to the accompanying drawing, forming part thereof, wherein—

Figure 1 is a side elevation of the case with the lid in open position.

Figure 2 is a plan view of Figure 1.

An essential feature of the design consists of alternate and parallel grooves and ribs forming a corrugated panel on the inner face of the bottom of the case, and a group of alternate and concentric grooves and ribs forming a circular corrugated figure in said panel.

I claim:

The ornamental design for an instrument case or similar article substantially as shown and described.

WILLIAM A. BAUM.
